Filed Feb. 4, 1966, Ser. No. 925

Term of patent 14 years

(Cl. D87—5)

FIG. 1

FIG. 3

FIG. 5

FIG. 2

FIG. 6

FIG. 4

FIG. 1 is a perspective view of a case for musical instrument or the like showing the top, front, and right end of my new design;

FIG. 2 is a rear elevational view thereof;

FIG. 3 is a top plan view thereof;

FIG. 4 is a bottom plan view thereof;

FIG. 5 is a left end elevational view thereof;

FIG. 6 is a right end elevational view thereof.

The design is characterized by the handle aperture being formed within the case body with edges of the body extending along the underside of the valence to form the outer portion of the handle, substantially as formed.

I claim:

The ornamental design for a case for musical instrument or the like, as shown and described.
